UNITED STATES PATENT OFFICE.

CLIFFORD H. GREEN, OF GRAND RAPIDS, MICHIGAN, ASSIGNOR TO NATIONAL PIANO MANUFACTURING COMPANY, OF GRAND RAPIDS, MICHIGAN, A CORPORATION OF ILLINOIS.

MULTIPLE-COIN CHUTE.

1,152,806.

Specification of Letters Patent.

Patented Sept. 7, 1915.

Application filed May 15, 1914. Serial No. 838,631.

To all whom it may concern:

Be it known that I, CLIFFORD H. GREEN, a citizen of the United States, residing at Grand Rapids, in the county of Kent and 5 State of Michigan, have invented new and useful Improvements in Multiple-Coin Chutes, of which the following is a full, clear, and exact description.

My invention relates to coin-chutes for 10 coin actuated automatic player pianos into which coins are dropped to select, through the medium of electrical devices, the piece of music which it is desired shall be played.

Heretofore a single coin was dropped into 15 the chute to cause the selection of the one tune desired, and if it were desired to repeat this tune another coin had to be dropped into the same chute for a repetition thereof.

20 The object of my invention is to enable as many coins to be dropped into the chute as it is desired to have a given piece of music repeated, and to enable the coins to automatically engage the electrical devices, one 25 after the other, to keep the music in position to engage the tracker-board and to repeat it again and again as many times as there are coins in the chute. This I accomplish by the means hereinafter fully described, and 30 as particularly pointed out in the claims.

In the drawings: Figure 1 is a front edge 35 view of a series of chutes having my improvements applied thereto. Fig. 2 is a side view of one of the same showing the position of the mechanism when the coins are supported upon the lower arm member of the angular rocking element. Fig. 3 is a similar view showing the position of the mechanism after the lowermost coin has 40 been released therefrom and the succeeding coin is held by the upper arm member ready to be released to cause the operation of the machine again. Fig. 4 is a rear end view of the lower end of the chute. Fig. 5 is a horizontal section through one of the chutes taken on dotted line 5—5, Fig. 4.

45 Referring to the drawings, A represents a vertically disposed tubular coin-chute, the bore of which in cross-section corresponds to a central section through the coin X used to operate the piano. The lower end of this chute is open and at a suitable distance above its lower end it is provided with a suitable opening a in its sides near its forward edges.

In order to discharge a coin from the lower end of the chute and intercept the coin next following the same, I have provided a vertical rock-spindle B, which is journaled in suitable bearings b, b, projecting from the rear edge of the chute near its lower end, substantially as shown. The lower end of this spindle has an arm C that extends laterally, then forwardly and then laterally again in the same direction as the lateral portion leading from the spindle. The normal position of this arm C is such that its free end c extends under the bore of the chute and intercepts and supports the lowermost coin. The upper end of the spindle is provided with an arm D that projects laterally in the opposite direction from arm C and then forward, and has its free end d bent toward the chute, and adapted, when said spindle is moved so as to withdraw the end c of arm C from under the chute, to enter openings a and intercept and cut-off the coin next above the space occupied by the lowermost coin. This arm D is engaged by a spring E which may be of any shape or design, but which is shown in the drawings to be substantially U-shaped with one end suitably fastened to the adjacent side of the chute and the other bearing outward against said arm. The spindle B is actuated by means of a link e whose rear end is pivotally connected in any suitable manner to arm D at a point a suitable distance from spindle B, and whose forward end is pivotally connected to the downwardly projecting arm f of an armature F, which latter is pivotally connected to the forward end of a bracket g that supports an electro magnet G, whose soft iron core attracts it when said magnet G is energized.

When in its normal position, end d of arm D will be withdrawn from opening a, and the coin will drop down past it and engage the rearward heel h of a trip H, which latter moves through a suitable slot in the front edge of the slot and is pivoted between lugs j projecting forward from the forward edge thereof. The portion of trip H, extending forward from its pivot, is considerably heavier than the heel h, and it has a post J extending therefrom in the vertical plane of its axis when the trip is in the position shown in Fig. 3 of the drawings. The upper end of post J comes under and supports the rearwardly projecting arm k

of a lever K that is fulcrumed to an upright m at a point in substantially the same transverse vertical plane as the front of the magnet. The arm k of this lever is kept normally pressing downward by means of a spring k' which is wound around the pivotal member of the lever K, and has one end extending to and over said arm k and its other end extending downward to and suitable secured in the insulating material M forming the support for the upright m. When the coin X engages the rear edge of the heel h of the trip H, shown in Fig. 2 of the drawings, and the post J of the latter moves out from under arm k, said arm assumes the position shown in Fig. 2 of the drawings. In order to restore the lever K to the position shown in Fig. 3, in which figure the lowermost coin has been discharged from the chute and the trip has gravitated back to the position shown in Fig. 3, I provide the lever K at a point above its fulcrum with an upwardly projecting lug o and provide the lower end of the downwardly projecting arm f of the armature with an inverted L-shaped finger n, which, when the armature is attracted by the magnet, engages lug o and lifts arm k of lever K to the position shown in Fig. 3, in which position post J will automatically move under its rear end and sustain it in a horizontal position. The forward end N of lever K is bent downward and when it is in the position shown in Fig. 3 of the drawings, this downwardly bent end N connects the metal terminal r of a circuit R with the leaf-spring terminal s of a circuit S, and when this lever is in the position shown in Fig. 2 of the drawings, said end N will move out of engagement with terminal r and press the leaf-spring terminal s into contact with the crooked end of a terminal t of a circuit T and close the circuit between T and S. The magnet circuit is instantly closed when the perforated sheet of music being played reaches its end. This energizes the magnet which attracts the armature F, and the latter, through the medium of the link e, rocks spindle B and projects the end of arm D through opening a in the chute and under the remaining coins to support them while the lowermost coin is being discharged. The trip H is tripped when the coins momentarily held by the arm D are released which tilts and releases the lever K permitting said lever to rock by force of gravity from the position shown in Fig. 3 to the position shown in Fig. 2, which closes the circuit T-S and causes the perforated music sheet after it has been rewound, to be played again. It is unnecessary to more than state the operation of the electrical circuits, and to broadly state the functions of the perforated

sheet music and tracker-board in view of the fact that these features of the automatic player piano to which my improvements are applied remain the same, and do not require any change in order to have my improvements applied to them, and, therefore, I have not described or illustrated these features.

What I claim as new is:

1. The combination with a tubular coin-chute adapted to hold several coins, one following the other, of an angular rocking element having a vertically disposed medial spindle member journaled in the rear of said chute, an arm member projecting from the upper end thereof the free end of which is adapted to enter the bore of the chute through a suitable opening in its side, and an arm member projecting from the lower end of said spindle whose full end extends transversely under the discharge end of said chute. 75

2. The combination with a tubular coin-chute adapted to hold several coins, one following the other, of an angular rocking element having a vertically disposed medial spindle member journaled in the rear of said chute, an arm member projecting from the upper end thereof the free end of which is adapted to enter the bore of the chute through a suitable opening in its side, and an arm member projecting from the lower end of said spindle whose full end extends transversely under the discharge end of said chute; said arm members being disposed in different horizontal planes and vertically at an angle to each other. 90

3. The combination with a tubular coin-chute adapted to hold several coins, one following the other, of an angular rocking element having an arm member movable into and out of the path of the coin gravitating through said chute, an arm member adapted to move laterally through said chute into

the bore thereof when said first mentioned arm member withdraws and vice-versa, a trip adapted to enter the bore of said chute through one vertical edge thereof and to be moved by the lowermost coin in the same, means released by said trip for closing an electric circuit, a magnet, a rocking armature arranged relatively to said magnet, and a connection between said armature and the angular rocking element for moving said arm member to discharge the lowermost coin in said chute and restore said trip to its normal position and open said electrical circuit. 110

4. Mechanism of the kind specified comprising a vertically disposed tubular chute, an angular rocking element having a vertical spindle member pivoted to one side of the chute, arm-members respectively projecting from the opposite ends of said spindle member in different but parallel horizon- 125

tal planes and in a vertical angle to each other, and adapted to alternately enter the path of the coin gravitating through said chute, an electro-magnet, an armature pivoted at one end adjacent the same, and a link connecting one of said arms to said armature.

5. Mechanism of the kind specified comprising a vertically disposed tubular chute, an angular rocking element having a vertical spindle-member pivoted to said chute, arm members respectively projecting from the opposite ends of said chute at suitable angles to each other and adapted to alternately enter the path of the coin gravitating through said chute, a trip pivoted mediate its ends to the chute on the side opposite the angular rocking element and adapted to enter the path of the coin gravitating through said chute, a lever; said trip being adapted to lock and release said lever; electrical circuits alternately opened and closed by

said lever, an electric magnet, an armature pivoted adjacent the same, and a link connecting one of said arms to said armature. 25

6. The combination with a vertical tubular coin-chute, of an angular rocking element having a vertical medial spindle member pivoted to one edge of said chute, and two lateral coin supporting arm-members 30 projecting in parallel horizontal planes from the opposite ends of said spindle member and at an angle to each other; said arm-members extending on opposite sides of said coin chute and being adapted to alternate 35 in their movement into coin engaging position.

In witness whereof I have hereunto set my hand this 11th day of May, 1914.

CLIFFORD H. GREEN.
